SHEET TRIMMING DEVICE

Robert Alonzo Williams, Chicago, Ill., assignor to
 Ditto, Incorporated, Chicago, Ill., a corpora-
 tion of West Virginia

Application December 29, 1941, Serial No. 424,745

12 Claims. (Cl. 164—73)

This invention relates to improvements in a sheet trimming device and in particular to improved means whereby a plurality of sheets may be trimmed at one time and to improved means for holding and handling the sheets during and after the trimming operation.

The trimming device which is herein shown is a preferred embodiment of my invention and is particularly well adapted for trimming the edges from a plurality of transversely slotted sheets in order to form a number of strips. In certain types of accounting and bookkeeping systems entries are made on a plurality of strips which are connected together at their ends by integral sheet portions, but which are separated by slitting at their intermediate portions. All of the strips on one sheet can thereby be handled as a unit, and a plurality of sheets may be stacked together with the corresponding entries on the various strips positioned directly over the corresponding entries and strips of the other sheets. By the single operation of trimming the edges from the whole stack of sheets, all strips bearing entries of one type will be separated from all strips bearing entries of another type, and the different groups of strips may then be handled as a unit. This series of operations is often times used when the entries from a particular group of strips are to be duplicated by means of a duplicating machine. The trimming device herein shown and described however is equally well adapted for the trimming of ordinary sheets, irrespective of the use to which they are later put.

It is a primary object of this invention to provide means for holding the different sheets in a predetermined stacked relationship with their edges exposed for trimming. This eliminates the necessity of holding the sheets by hand, and the danger of cutting the operator's fingers. Furthermore my invention contemplates the provision of cutting wheels rather than the pivoted knives which are often used in trimming devices of this sort. This further eliminates any danger of cutting the operator's fingers which is likely to occur when the knife blade on a trimming device of that sort is dislodged and falls from its upright position. Furthermore by the use of cutting wheels, I have found that it is possible to trim at one time a greater number of sheets than when other types of cutting means are used.

Means are also provided to maintain the several groups of strips in alignment during and after the trimming operation and preparatory to the removal of the strips from the trimming device. Improved means are also provided for the re-

moval of each group of strips from the device without disturbing the arrangement of the group, or without destroying their prearranged order.

Various other objects, features and advantages 5 of my invention will become apparent as the description proceeds. Reference is made to the accompanying drawings in which like reference numerals refer to like parts and in which drawings—

10 Fig. 1 is a plan view of a preferred embodiment of my invention;

Fig. 2 is a section taken along line 2—2 of Fig. 1;

Fig. 3 is a section taken along line 3—3 of 15 Fig. 2;

Fig. 4 is a section taken along line 4—4 of Fig. 1;

Fig. 5 is an enlarged section taken along line 5—5 of Fig. 2;

20 Fig. 6 is a perspective view of the block and pin arrangement which holds the several groups of strips;

Fig. 7 is a detailed section taken along lines 7—7 of Fig. 8 and of Fig. 2;

Fig. 8 is a detailed section taken along line 25 8—8 of Fig. 7;

Fig. 9 is an elevation of the block and pin arrangement shown in Fig. 6, also showing the application thereto of a spring clip whereby holding of the several groups of strips may be facilitated.

Fig. 10 is an end view of the parts shown in 30 Fig. 9; and

Fig. 11 is a section taken along line 11—11 35 of Fig. 3.

Reference numeral 12 designates a sheet receiving base, which may be a block of wood of the desired size. The base is mounted on two U-shaped brackets 13 and 14 which extend longitudinally thereof, the outer and downwardly extending ends of which form the feet 15 and 16 upon which the device rests. The central portion of the brackets 13 and 14 comprises channel members 17 and 18 which are so disposed that they face inwardly. An upper clamping board 19 is suitably hinged to the base 12, and is provided with a handle 20 by means of which it may be raised from an operative position directly overlying the base into the upright position shown in Fig. 2.

The upper clamping board 19 is provided at its side edges with metal strips 21 and 22 which are screwed thereto by suitable screws 51 as shown in Fig. 5. The strips are extended rearwardly of the upper clamping board, and a pin 24 is secured to

each of said strips at their extended portion, each of the pins projecting outwardly. Blocks 25 and 26 are suitably secured to the brackets 13 and 14 at the rear portions thereof, as shown in Figs. 2 and 7. Block 26 is provided with a bore 27 and an intersecting slot 28, the pin 24 extending into the slot, and a spring 29 being disposed in the bore 27 to urge the pin and the upper clamping board downwardly. The block 25 is provided with similar means for receiving another pin 24 so that it will be seen that the hinge mounting of the upper clamping board 19 is effected by the co-operation of the pins 24 with the blocks 25 and 26. The block 26 is provided with a cap 30 which is secured thereto by suitable screws 32 in order to confine the spring 29 in the bore 27. A similar cap 31 is shown for the block 25, which is secured thereto by screws 33.

The floating hinge arrangement herein shown and described permits the upper clamping board 19 to be disposed in parallel relationship to the base 12 when in operative position irrespective of the thickness of the stack of sheets. The spring 29 also serves to maintain the upper clamping board in upright position as shown in Fig. 2 by virtue of the over-center action resulting when the flat spot 34 at the rear end of the strip 22 engages the bracket 14. The rear end of the strip 21 is similarly shaped.

The base 12 is provided with a channel 35 formed in its upper surface along its left edge, and with a channel 36 formed in its upper surface along its right edge. As shown in Fig. 4, blocks 37, 38 and 39 are disposed in end to end relationship in the channel 35. In channel 36 is disposed a block 40. Each of the blocks 37, 38 and 39 is provided with a plurality of pins 41 which extend above the surface of the base 12, these pins being provided with annular grooves 43 as shown in Fig. 4. Similarly block 40, which in length is equal to the length of all three of the blocks 37, 38 and 39, is provided with a corresponding number of pins 42. Both sets of pins, 41 and 42, are preferably equally spaced from each other, and the corresponding pins of one set are directly opposite to the corresponding pins of the other set. As shown in Fig. 4, the channel 35 is also provided with blocks 44 which merely serve to fill up the channel. Similar fill blocks 44 are provided for channel 36, and these blocks are provided with pins 45 by means of which they may be secured to the base 12.

Grooves 47 and 48 are provided in the upper clamping board 19 in order to receive the upper portion of the pins 41 and 42 when the upper clamping board is in its operative position. One wall of the grooves 47 and 48 is formed by the strips 21 and 22, and one wall of the channels 35 and 36 may similarly be formed by the strips of metal 49 and 50 as shown in Fig. 5. These strips 49 and 50 may be suitably secured to the base 12 by means of screws 52. As shown in Fig. 7, the rear edge of the base 12 may be protected at its right-hand portion by an end plate 53, secured thereto by screws 54, against which the end portion of the strip 22 may abut when the upper clamping board is in its upright position as shown in Fig. 2. A similar end plate is provided for the left-hand portion of the rear edge of the base 12.

As shown in Fig. 1, a stack of sheets 96 may be positioned on the base 12, each sheet comprising a plurality of strips 97 which are separated by slits 100 in the intermediate portions thereof, but which are joined together by the marginal edge portions 98 of the sheet. Each strip is provided

with perforations 99 just inwardly from the edge portions 98. The strips of the different sheets are held one over the other by means of the pins 41 and 42 which extend through the perforations 99. After the edge portions 98 have been trimmed from the sheets, six groups of strips may be removed at one time from the trimming device by removing one of the blocks 37, 38 or 39. Removal may be facilitated by means of a clip 94 which can engage the pins 41 in the grooved portions 43 thereof.

The trimming or cutting means is mounted upon a carriage which is designated generally by the reference numeral 55. The carriage comprises a cross member 56 which is in the form of a channel open at the bottom and which serves as a housing. Plates 57 and 58 are secured to the housing 56 at a point inwardly of the ends of the housing, these plates being provided with lugs which extend upwardly adjacent the channels 17 and 18. A pair of rollers 59 is carried by the plate 57, and a corresponding pair of rollers 60 is carried by the plate 58, these rollers fitting into the channel portions 17 and 18 of the mounting brackets 13 and 14. As shown in Fig. 7, the roller 60 rides upon the lower member 61 of the channel 18, and slightly clears the upper member 62 of the channel. Each roller may be mounted in its respective plate by means of a pin 63, and the roller may also be provided with a flange 64 which serves to maintain the parts in spaced relationship, this arrangement being shown in Fig. 7. Each of the plates 57 and 58 may be rigidly secured to the housing 56 by means of screws 65 as shown in Fig. 3. It will thus be seen that the housing and the carriage as a whole which is mounted on the housing may freely slide longitudinally of the base 12 by virtue of the channel and roller arrangement.

Mounted on the carriage are upper cutting wheels 67 and 68 and lower cooperating cutting wheels 69 and 70. The upper cutting wheels may be serrated at their cutting edge as shown in Fig. 2. The cutting wheels are mounted on plates 71 and 72 which are welded or otherwise secured to the housing 56. The upper cutting wheels 67 and 68 are provided with shafts 73 and 74 which are journaled in the plates 71 and 72. Similarly the lower cutting wheels 69 and 70 are provided with shafts 75 and 76 which are journaled in the plates 71 and 72. Gears 77 and 79 are pinned to the shafts 73 and 75 and mesh with each other. Similarly gears 78 and 80 are pinned to the shafts 74 and 76.

A shaft 81 is disposed in the housing 56 and at its right-hand end is provided with a crank 82, the shaft being journaled in the lower portions of the plates 71 and 72. The shaft 81 has pinned to it pinions 83 and 84 at either end thereof, which engage idler gears 85 and 86, as shown in Fig. 3, the idlers in turn meshing with the pinions 79 and 80. It will be seen therefore that as the crank 82 is turned, the cutting wheels will be driven.

On the upper surface of the housing 56 is mounted a bearing plate 87, and a shaft 88 is journaled therein. A pinion 89 is secured to the upper end of the shaft 88, and is held in spaced relationship from the bearing block by means of a collar 90. A rack 91 is secured to the underside of the base 12, and is engaged by the pinion 89 so that as the pinion is caused to rotate, the carriage will be caused to slide longitudinally of the base. The shaft 88 extends through the housing 56 and is provided with a

bevelled gear 92 which meshes with a bevelled gear 93 carried on the shaft 81. As the crank 82 is rotated, it will cause the carriage to ride backwardly or forwardly and at the same time drive the cutting wheels which will serve to trim the marginal portions 98 from the stack of sheets 96. It will be noted that the side edges of the upper clamping board are offset inwardly from the side edges of the base 12, and that the lower cutting wheels 69 and 70 are provided with a plane surface which permits the cutting edge to be disposed very closely adjacent the base. The upper cutting wheels 67 and 68 are also provided with a plane surface so that the upper and lower cutting wheels may overlap each other to an extent equal to the maximum thickness of the stack of sheets which are to be cut. The extra space provided by the offsetting of the edges of the upper clamping board serves to accommodate the upper cutting wheels. It will be noted that one of each pair of cutting wheels is serrated in order to provide more efficient cutting action. By the arrangement herein shown I secure a positive drive for both the cutting wheels and for the travel of the carriage. The rack and the rollers upon which the carriage is mounted are disposed below the base where they can not be damaged, and will not interfere with the raising and lowering of the upper clamping board. The gearing by means of which the cutting wheels are driven is enclosed in the housings 101 and 102 shown in Figs. 3 and 11, these housings being suitably secured to the plates 71 and 72. It will be seen therefore that all the moving parts, with the exception of the cutting wheels, are enclosed, and such parts may be lubricated without any danger of smearing the sheets which are to be trimmed, or the operator's hands.

In operation the carriage 55 is moved, by turning the crank, to the rear end of the machine, and the upper clamping board is elevated to the position shown in Fig. 2. A stack of sheets 96 is placed on the base, perforations 99 being fitted over the two series of pins 41 and 42. The upper clamping board is then brought down into operative position, in which it is disposed parallel to the base, and makes full contact with the stack of sheets 96. The crank 82 is then turned which causes the carriage to be advanced forwardly, and the cutting wheels to trim off the marginal edge portions 98 of the stack of sheets, which edge portions extend outwardly beyond the base at either edge thereof. When the carriage 55 has reached the limit of its travel, the stack of sheets will have been separated into a plurality of groups of strips. These groups may be removed six at a time, after the upper clamping board has been elevated into its upright position, by means of removing the blocks 31, 38 and 39 one at a time. The clip 94 can be used to facilitate this removal. It will be observed that the length of the clip is approximately equal to the length of the block 31, and that the clip may be shifted longitudinally of the block step by step so as to expose one pin at a time. This permits the removal of one group of strips at a time as shown in Fig. 9, but prevents any of the other groups of strips from becoming disengaged from their respective pins.

While the form and arrangement of parts as above described are preferred, the invention is not to be limited to the arrangement shown except so far as the claims may be so limited, it being understood that changes might well be made in the construction and arrangement of the parts

without departing from the spirit of the invention.

I claim:

1. A sheet trimming device comprising a sheet receiving base, sheet clamping means mounted on the upper surface of said base, a carriage slidably mounted on the underside of said base, two pairs of rotatable cutting wheels mounted on said carriage in a position to trim the extended edges of a stack of sheets clamped on said base without interfering with the operation of said clamping means, and a common drive shaft disposed in said carriage for rotating both of said pairs of cutting wheels.

2. A sheet trimming device comprising a sheet receiving base, a carriage slidably mounted on the underside of said base, said carriage including vertically disposed end members extending upwardly beyond the upper surface of said base and in juxtaposition to the side edges thereof, a pair of rotatable cutting wheels journaled one above the other in each of said end members in a position to trim both of the extended side edges of a stack of sheets positioned on said base, and means to cause said cutting wheels to be rotated and said carriage to move along said base.

3. A sheet trimming device comprising a sheet trimming base, clamping means hinged to said base and cooperating with the upper surface thereof to hold the sheets in such a manner that their edges extend beyond the side edges of said base and said clamping means, a carriage mounted on the underside of said base and provided with cutting wheels disposed in a position to engage said extended sheet edges, and means to cause said carriage to travel from one end of said base to the other as said cutting wheels are rotated.

4. A sheet trimming device comprising a sheet receiving base, brackets upon which said base is mounted, the central portions of said brackets comprising channels, a housing positioned beneath said base, rollers associated with said housing and disposed in said channel so as to permit said housing to be moved longitudinally of said base, a pair of cutting wheels carried on said housing and disposed so that their bight is immediately adjacent the side edge of said base, a drive shaft for said cutting wheels disposed within said housing, and means associated with said drive shaft and engaging said base for causing longitudinal displacement of said housing and said cutting wheels.

5. A sheet trimming device comprising a sheet receiving base, brackets upon which said base is mounted, the central portions of said brackets comprising channels, a housing positioned beneath said base, rollers associated with said housing and disposed in said channel so as to permit said housing to be moved longitudinally of said base, vertical members at the ends of said housing extending upwardly beyond the top surface of said base, cutter wheels journaled in said vertical members, a shaft disposed within said housing and journaled in said vertical members, a rack secured to said base, a cooperating pinion associated with said housing and adapted to engage said rack, a crank for rotating said shaft, and means for driving said pinion and said cutter wheels from said shaft.

6. A sheet trimming device comprising a trimming board, clamping means pivotally mounted on the upper surface of said trimming board, a carriage slidably mounted with respect to said board and disposed beneath the same, upper and lower cutting wheels mounted on said carriage in such a position as to trim the extended edges of

a stack of sheets clamped on said board, said lower cutting wheel having a plane surface disposed closely adjacent the side edge of said board and the periphery of one of said cutting wheels being serrated.

7. A sheet trimming device comprising a sheet trimming board, clamping means mounted on the upper surface of said trimming board and cooperating therewith to hold the sheets in such a manner that their edges extend beyond the side edges of said sheet trimming base and said clamping means, a carriage slidably mounted on the underside of said board, upper and lower cutting wheels mounted on said carriage in such a position as to trim said extended edges, said lower cutting wheel having a plane surface disposed closely adjacent the side edge of said board and said upper cutting wheel having a plane surface overlapping and in contact with the plane surface of said lower cutting wheel.

8. A sheet trimming device comprising a sheet receiving base, a channel formed in the upper surface thereof, a removable block disposed in said channel, and a plurality of pins embedded in said removable block, said pins being formed with annular grooves near the ends thereof whereby said pins may be positively engaged in said grooves by a spring clip in order to remove the pins and their associated block from said sheet receiving base.

9. A sheet trimming device comprising a sheet receiving base, a channel formed in the upper surface and at one edge thereof, a removable block disposed in said channel, a plurality of pins embedded in said removable block, said pins being formed with annular grooves near the ends thereof whereby said pins may be positively engaged by a spring clip in order to remove the pins and their associated block from said sheet receiving base, and cutting wheels slidably and rotatably mounted with respect to said base adjacent to said channel so as to engage the marginal edges of a stack of sheets held on said base by said pins.

10. In combination with a sheet trimming device, a sheet receiving base having a channel formed therein, a block provided with a plurality of pins disposed in said channeled base, each of 5 said pins being adapted to hold a group of perforated strips, and each being provided with an annular groove, and a clip constructed so as to slidably engage said pins in said grooved portions to facilitate handling of the assembly, and 10 to prevent disengagement of said strips from said pins.

11. In a device for trimming the edges from a stack of sheets, each sheet being made up of strips connected together at their ends by integral sheet 15 portions and being separated at their intermediate portions by slits, a base adapted to receive a stack of sheets with the edge portions of each extending laterally beyond the edge of said base, clamping means for said stack of sheets pivotally mounted on said base, rotatable cutting means including a carriage associated with said base at the underside thereof and adapted to slide longitudinally thereof and to trim said edges, said rotatable cutting means comprising an upper and a lower wheel, the peripheries of which 20 overlap each other by a distance equal at least to the thickness of said stack of sheets.

12. In a device for trimming the edges from a stack of sheets, each sheet being made up of strips 25 connected together at their ends by integral sheet portions and being separated at their intermediate portions by slits, a base adapted to receive a stack of sheets with the edge portions of each extending laterally beyond the edge of said base, clamping means for said stack mounted on said base, a carriage including rotatable cutting means associated with said base at the underside thereof and adapted to slide longitudinally thereof and to trim said edges, said rotatable cutting 30 means including a serrated cutting edge.

ROBERT ALONZO WILLIAMS.
